UNITED STATES PATENT OFFICE

2,364,800

MOP

Alexander Jean Lipstock, Brooklyn, N. Y., assignor to The Industrial Home for the Blind, Brooklyn, N. Y., a corporation of New York

Application June 11, 1942, Serial No. 446,553

2 Claims. (Cl. 15—229)

My invention relates to floor or ship mops, and is an improvement on those now on the market, and particularly that of United States Patent No. 1,450,556, dated April 3, 1923.

To build the mop the operator grasps a number of loose strands of suitable material, usually fibrous material such as cotton yarn, the strands are laid lengthwise in a pile on a piece of goods that will form a cuff, the strands as noted are placed more thickly in the middle than at the ends of said cuff that forms the head of the mop, when this has been done the cuff and the material therein are stitched with a row of stitching at the upper and lower end (see Fig. 2). Then the cuff and the material therein is folded over in the middle. After this has been done the cuff or strip of material holding the many strands in place, is tucked in at the ends, and the cuff with the strands is placed again in the machine and stitched with several shorter rows of stitching between the two rows already made, this making a very strong heading for the mop and holding each and every strand in place. At suitable spaced distances is placed metallic or other eyelets so that when the mop is worn out it may be taken from the handle and replaced with another one. The mop is held to the handle that has already been prepared to receive it by a bolt and nut which passes through a central bore in the handle at its lower end.

When it is desired to replace a mop, the thumb nut or its equivalent is released from the screw which passes through the eyelet, the bolt being removed, the old mop is disposed of, while the handle is kept, and a new mop applied by reinserting a fastening element through the mop cuff and through the handle.

One of the many objects of my invention is the saving of the handle of the mop, which in many cases when the mop is worked out, the handle and what remains of the old mop is cast aside, in other words discarded. Today handles are among the many products that are rare and expensive, thus it will be readily seen that with my improvement, for instance on board of ship where space is at a premium, that only the mops themselves may be crated and stored, once the full complement of handles have been received, it will only be necessary to have a few in reserve in case an accident happens to any one or more of them, thus just as soon as one mop is worked out it is taken from the handle and thrown away and a new one applied.

The mop cuff having the metallic eyelets is always ready to be applied at a moment's notice,

then again a heavy twine may be used to secure the mop to the handle should the bolt and nut be objectionable. Again it may be desired to have a thin metal plate extending around the outside of the cuff and under the head of the bolt and nut, these are suggestions only because it may be desired, yet with metal at a premium it may be objectionable, yet the mop itself is good and efficient without having such a reinforcement about it.

It will be seen that where the mop heads are provided as units without the handles they can be accommodated aboard ships and other places without requiring as much space as would otherwise be required if each mop head were mounted on a handle. The reinforcement of the cuff at the head of the mop, provided with the metal eyelets or other equivalents, provides a very reliable and compact unit, the mop and handle when assembled forms a neat, compact, cheap as well as a very handy implement.

The invention will be more fully understood when read in connection with the drawing which forms a part of this application and the novelty of the same pointed out in the description and also in the claims.

In the drawing, Fig. 1 is a view of my mop as applied to the handle.

Fig. 2 is an enlarged view of the cuff as it is applied to the strands before being folded upon itself lengthwise, and when only two rows of stitching is done so as to hold the mass in proper position.

Fig. 3 shows the cuff after it has been folded and stitched, also it has received the metallic eyelets.

Fig. 4 is a cross section through the cuff and handle, showing the method of applying the mop to the handle.

Fig. 5 shows the cuff provided with a metallic reinforcement, through which the eyelets passes, making a very secure method of holding the same compact.

Fig. 6 is a detached detail of another form of fastener that may be applied to the mop.

Fig. 7 is a view in elevation of a modified construction in which the cuff is applied to a handle to form a dauber.

Referring to the drawing, the strands 10 of material that is to form the mop are laid transversely of the cuff 11, of some strong material that has been provided, such for instance as a light canvas or heavy cotton (see Fig. 2) the strands are placed close together central of the

cuff, or it may be said to be piled up in the center part 12, while towards the ends 13 and 14 the strands are spread out more, so that when the two ends 15 and 16 are overlapped, to receive the attaching bolt 17, that the two ends will not be any thicker than the central part 12 of the mop and the same will be held secure by a winged nut 18. Thus by this means there will practically be about the same number of strands forming the mop at every point about the handle. When the mop is thus formed, a row of stitching is placed at the top 19 and at the bottom 20, to hold the strands in proper relation with the cuff that forms the head of the mop before the cuff and the strands are folded upon themselves to make a compact unit.

As has been noted when the cuff and strands have been folded upon itself, the cuff may provide a covering for the strands 10 on the inside and on the outside, then the double thickness of the cuff is stitched together as shown at 21, the short stitches 21 are made from the outer edge for a short distance as shown (see Fig. 3) so as to reinforce the outer edges of the cuff and thereby reinforce the same.

After the stitching has been made the so formed mop is then provided with eyelets 22 of some character, either stitching or by use of metal eyelets, the latter is preferred, as they hold the strands and cuff into proper position at all times, and also under all usages, and when applied to the handle with the bolt 17 and winged nut 18, the strands will be divided so that the mop will be perfectly balanced about the end of the handle.

The manner of forming the cuff thus described, with the strands unevenly distributed therein is to get a balanced article, but the strands may be placed evenly along the whole surface of the cuff before stitching, though the effect is not quite as pleasing, but the working effect of the article will not be impaired as the article will work just as well, the only reason for providing the reduced ends as described is to get a symmetrical looking balanced article, but it may be desired to place the same number of strands all across the cuff.

Of course should the eyelets be stitched it would be impossible to use any reinforcement strip over the cuff, but when the eyelets are metal then the eyelets pass through the reinforced strip 23 and the head of the mop making a very secure and lasting binding.

It may be desired to have two bolts through the mop head and handle just for security, if so it would only be necessary to bore another hole in the handle at right angles to the other one, and to provide an extra set of eyelets in the cuff so as to extend the bolt through, of course such an arrangement would make a very strong at-

achment, but for ordinary purposes it is believed one bolt and nut will suffice.

It will be seen that the mop as constructed may be used without in any way injuring any part of the household or the ship, that it comes in contact with. It might be advisable in some cases to provide a flat head on both sides of the fastener such as is shown in Fig. 6, the internal nut 25 provides no outer extensions whereby it may mar any part that it comes in contact with.

Again, with this construction it is possible to make daubers in this fashion, as they could be made very cheap and would not be necessary to use an adhesive to hold the fibers together, as the outer sheathing or cuff would hold the same, while the fastening would hold the dauber to the handle.

In the modified construction of Fig. 7, the mop head *a*, constructed substantially in accordance with the illustration in Fig. 5, is applied to an elongated portion *b* of a handle *c*, and a reinforcing strip *d* surrounds the cuff as in the other embodiment, and the reinforcing strip and cuff are secured to the elongated head by fastenings *e* of any appropriate type such as illustrated in the drawing.

What I claim as new and desire to obtain Letters Patent on is:

1. A mop comprising a cuff consisting of a strip of material adapted to be wrapped around a mop stick with the ends of the cuff overlapping, strands of material carried by the cuff, the said strands being less numerous at the ends of the cuff than in the central portion thereof, in order that when the ends of the cuff are overlapped and contiguous, the strands at the overlapped portion will approximate the bulk of the strands in the intermediate portion thereof, a reinforcing band applied to the exterior of the cuff, means for attaching the said reinforcing band to the cuff, and removable means for attaching the encircling cuff to the mop stick.

2. A mop comprising a cuff consisting of a strip of material adapted to be wrapped around a mop stick with the ends of the cuff overlapping and contiguous, strands of material carried by the cuff, the said strands being less numerous at the ends of the cuff than in the central portion thereof, in order that when the ends of the cuff are overlapped, the strands at the overlapped portion will approximate the bulk of the strands in the intermediate portion thereof, eyelets through the cuff and strands approximately centrally of the length of the cuff, eyelets at the ends of the cuff where it overlaps, and fastening means extending through the eyelets and through a mop stick which the cuff surrounds.

ALEXANDER JEAN LIPSTOCK.
